(57) **CLAIM**

The ornamental design for a mount for a medical imaging device, as shown and described.

DESCRIPTION

FIG. 1 is a front perspective view of a mount for a medical imaging device

FIG. 2 is front perspective view thereof.

FIG. 3 is a front view thereof.

FIG. 4 is a rear view thereof.

FIG. 5 is a top view thereof.

FIG. 6 is a bottom view thereof.

FIG. 7 is a first side view thereof.

FIG. 8 is a second side view thereof; and,

FIG. 9 is a perspective side view thereof.

The broken lines in the Figures (e.g., depicting unclaimed medical device and unclaimed electronic device in FIGS. 1 and 7-9) show environmental context only and form no part of the claimed design.

1 Claim, 9 Drawing Sheets
